TRIPLE VALVE FOR DIRECT ACTING
AUTOMATIC BRAKES

Florentin Kasantzeff, Berlin, Germany

Application May 27, 1932, Serial No. 614,003

2 Claims. (Cl. 303—35)

This invention relates to a triple valve or distributor for pneumatic brakes of the direct acting automatic type.

In my copending application, Ser. No. 446,731,

5 I have described a triple valve having a regulating chamber inserted between the brake cylinder and the train pipe and fed with compressed air through narrow passages which offer such a resistance to the streaming air, that the brake action 10 is deferred for a certain time space, and thereby even large alterations of pressure in the train pipe and even in long trains come into action sufficiently simultaneously on the brakes of the single cars for obviating undue stresses in 15 the car couplings and buffers.

The new invention concerns a further development of the said construction and consists therein, that the regulating chamber, which by its only slowly changeable air pressures governs 20 the entrance and exhaust of air on the brake cylinder, receives a certain minimum initial air amount with an acceleration by aid of an initiating chamber adjoined to said regulating chamber through its air feeding valve by a large passage 25 and fed through the above named narrow throttling passage from the auxiliary reservoir. The air volume contained in said initiating chamber thereby streams quickly into the regulating chamber, as soon as both said chambers are 30 brought into connection with each other for braking, and thus the regulating chamber comes quickly on a certain initial pressure, which causes also in the brake cylinder a certain initial pressure to be quickly produced, so that the brake 35 blocks become loosely applied to the running wheels. This has the advantage that the brake blocks are instantly and softly applied, and the real braking action, which subsequently begins with a certain hesitation, becomes especially free 40 from shocks and very uniform on all cars of the train.

A further valuable detail of the invention consists in a regulating valve inserted in the throttled feeding channel and in the exhaust channel of the regulating chamber in such way that it allows of adjusting both said channels to different throttling actions or to close them fully. Thereby the time spaces needed for the full braking 50 and brake releasing actions can be regulated according to the requirements, and by fully closing said valve any given condition of braking or brake releasing can be maintained at will, for example for handling an uncoupled car.

55 In the drawing

Fig. 1 is a diagram showing the mode of action of the new triple valve, and

Fig. 2 is a longitudinal section of said triple valve.

The diagram Fig. 1 shows the time as the abscissa, and the braking pressures as the ordinate. The line *a* corresponds to the action obtained according to the above named copending application 446,731, and line *b* shows the new action. Whereas according to line *a* the pressure in the regulating chamber and correspondingly also in the brake cylinder successively ascends from zero to the maximum and on any point of said line the brake blocks become applied, now, according to line *b* a quick initial increase of pressure is obtained for applying the brake blocks, and thereafter the pressure is gradually increased up to the maximum.

The triple valve according to Fig. 2 contains 20 for this purpose three main parts (as in the mentioned copending application): a regulating pressure producer 1, a regulating chamber 2 fed with the pressure from producer 1, and a brake cylinder-feeding device 3 governed by said regulating pressure.

The regulating pressure producer 1 contains 25 five chambers 4, 5, 6, 7, 8 separated from each other by an intermediate wall 9, a diaphragm 10, a further intermediate wall 11 and second diaphragm 12. The first diaphragm 10 is provided 30 with a hub 13 extending with a close fit through the intermediate wall 11 and perforated at 14. A double seat valve 15 is arranged in an opening of the first intermediate wall 9 adapted to alternately close and open both a passage through 35 said wall also said perforation 14 in hub 13. The second diaphragm 12 is provided with a casing 16 containing a spring 17 and an abutment, plate 18 pressed against a stop 16a on said diaphragm by said spring and holding said spring under a certain predetermined tension according to the 40 desired maximum pressure in the regulating chambers 2, 5 and arranged opposite to the hub 13 so as to be engaged by the latter as soon as both diaphragms 10 and 12 approach each other.

The said uppermost chamber 8 is open to a 45 constant pressure reservoir 23 (supplemental reservoir) which functions to load the diaphragm 12 by an essentially constant pressure.

The next chamber 7 below said diaphragm 12 is 50 connected through a passage 22 to the train pipe and serves to bring the variations of train pipe pressure into effect on the whole regulating pressure producer 1.

The next chamber 6 is open to the atmosphere 55

through a channel 21 and in cooperation with the said valve 15 and channel 14 serves for exhausting air from the chamber 5 and from the regulating pressure chamber 2 connected thereto.

- 5 Finally, the lowermost chamber 4 is connected to the auxiliary air reservoir through a channel 19 and a back pressure valve 48 having a small perforation 49. This chamber serves to feed air to the chamber 5 and to the regulating pressure 10 chamber 2 connected thereto, in cooperation with the valve 15.

The said channels 21 and 19 offer certain resistances to the streaming air for consuming a certain measured time in exhausting or feeding said 15 chambers 5 and 2. For producing and regulating such resistances, a cock 60 having narrow throttling passages 60a and 60b is inserted into said channels 21 and 19. Said cock also serves for entirely closing said channels in case it is required 20 that a certain pressure in chambers 5 and 2 shall be maintained for a long time, for instance a pressure of 0 atmosphere, when a car is to be shunted.

The said chamber 4 is of such size that the compressed air contained in it (for example having 25 5 atmospheres) at the moment of opening of the valve 15, through the chamber 5 and the passage 20 fills the regulating chamber 2 up to a certain initial pressure (of for example 0.25 atmospheres), and thereafter the further filling up of 30 chamber 2 proceeds more slowly according to the resistance of the narrow feed passage 60a in cock 60.

For feeding compressed air to chamber 4, a feeding valve case 24, having a passage 24a, is 35 provided, and said passage 24a is connected through a passage 45 to said train pipe passage 22. Said valve case 24 is closed on top by a diaphragm 25. A valve 25b, having a bore 25a, is connected to said diaphragm 25 and fits closely 40 into said case 24. A spring 25c presses said valve 25b upwardly. A narrow bore 24b is arranged in said case 24 in such manner that it is closed by the head of valve 25b in the lowermost position of the latter. The space below said diaphragm 25 45 is connected to the atmosphere by a passage 26.

From the above said passage 45, a further passage 46 leads to a back pressure valve 47 and through a passage 47a to the said back pressure valve 48, 49 and to the auxiliary air reservoir.

50 The entire regulating pressure producer 1 and the feeding valve 24, 25 operate as follows.

In filling the train pipe, the air enters through 55 passages 22, 45, 46, 47, 47a, 49 into the auxiliary reservoir and at once into the passage 19 and chamber 4. Further, the air enters through passage 24a into the valve case 24, and through the valve bore 25a to the constant pressure chambers 23a and 23. At once, a small amount of air escapes through the bore 24b to the space below 60 diaphragm 25 and thence through passage 26 to the atmosphere. As soon as the constant pressure chamber 23 is filled up to a certain pressure depending upon the sizes of diaphragm 25 and of the spring 25c, said diaphragm 25 moves downwardly. The attached valve 25b then first closes the passage 24a, so as to discontinue filling chamber 23. At once the entrance of air to the bore 24b ceases, and the passage 26 completely exhausts the space below diaphragm 25, so that the 65 latter completely descends and closes said bore 24b. In this way the running position is attained, in which chamber 23 has full pressure, and chamber 2 is still without pressure.

In braking, a pressure reduction is produced in 70 the train pipe and through passage 22 in chamber

ber 7, so that diaphragm 12 (loaded from above by the full pressure existing in chamber 23) moves downwardly. Thereby valve 15 is lifted from its seat, and the air from chamber 4 streams through valve 15, chamber 5 and passage 20 to the regulating chamber 2, in which it suddenly produces a certain initiating pressure. Thereafter further air follows through the narrow passage 60a so as to raise said initiating pressure more slowly. This rise is finished as soon as the rising pressure 10 in chamber 5 suffices for raising the diaphragm 10 so as to allow valve 15 to close.

An excessive reduction of train pipe pressure, arising in braking by any mischief, would result in an excessively high pressure in chamber 2. 15 This is obviated by the yielding effect of spring 17, which in such cases is compressed and allows the valve 15 to close.

In brake releasing, the effects are the same as in filling the brake, with the addition that the 20 pressure existing in chambers 2 and 5 lifts the diaphragm 10 and thereby opens the channel 14 as long, until chambers 2, 5 have been exhausted through passage 14, chamber 6 and throttling cock-boring 60b to the atmosphere. 25

Thus, briefly stated, the regulating chamber 2, in running state remains without pressure; in braking it receives at first an initial pressure of say 0.25 atmospheres and thereafter, slowly, a higher pressure up to say 1.2 atmospheres. In 30 brake releasing said pressure is slowly diminished to atmospheric pressure. Any such pressure is automatically conserved as long as the corresponding train pipe pressure is conserved.

Now, it is only necessary to utilize the said various pressures for producing completely proportionate pressures in the brake cylinders. This is done by the brake cylinder feeder 3 as follows.

The brake cylinder feeder 3 contains four chambers 30, 31, 32 and 33, separated from the regulating chamber 2 and from each other by diaphragms 34, 35, 36 of different diameters and by an intermediate wall 37. The chamber 30 is open to the atmosphere through a channel 38. The next chamber 31 is connected by a channel 39 to a cock 40 having a groove 41 adapted to connect said channel to the atmosphere and a cross-bore 42 adapted to connect said channel 39 to a further channel 43 opening into the chamber 32 which is connected to the brake cylinder at 44. Said cock serves for either opening the chamber 31 to the atmosphere, so that the diaphragm 35 becomes ineffective (for loaded vehicles), or for connecting the chambers 31 and 32 to each other, so that the diaphragm 36 becomes ineffective (for empty vehicles), so as to produce in chamber 32 for instance a desired maximum brake cylinder pressure of 3.6 or 2 atmospheres respectively, if the regulating pressure in chamber 2 amounts to 1.2 atmospheres. 55

The chamber 33 is connected to the said train pipe through the passages 22, 45, 46, 47 and 47a. Said chamber 33 is further connected to the auxiliary reservoir through the said bore 49 of valve 48. Thereby the auxiliary reservoir is slowly filled through said bore 49 from the chamber 33 and from the train pipe, but quickly delivers air through the valve 48 for filling the brake cylinder. 60

The diaphragms 34, 35, 36 are joined together by a hub 50 in which a channel 51 is so arranged that it leads from the atmospheric chamber 30 to the brake cylinder chamber 32 through a double-seat valve 52 extending through the chamber 32 and through an opening of a valve casing 52a se- 70

cured in the intermediate wall 37. Both valves 52 and 48 are held on their seats by a common spring 53.

The brake cylinder feeder 3 acts as follows. As long as atmospheric pressure is present in the regulating chamber 2 (during filling the brake system and while releasing the brakes) the diaphragms 34, 35, 36 remain in their middle position and the brake cylinder chamber 32 is open to the atmosphere. As soon as (for braking) a pressure reduction is produced in the train pipe and thereby an initiating pressure jerk and thereafter a slowly rising regulating pressure is produced in the regulating chamber 2, the diaphragms 34, 35, 36 go to the right under the action of the regulating pressure and by their hub 50 take along with them the double valve 52 at first quickly and thereafter slowly. Thereby air from the chamber 33 through valve 52, 52a enters the chamber 32 and the brake cylinder, first in a certain large amount sufficient for quickly applying the brake blocks to the wheel rims, and thereafter more slowly for exerting the slowly rising braking pressure until equilibrium is restored. The brake cylinder pressure thus balanced against the regulating pressure depends upon the area proportions of the diaphragms 34 and 35 or 34 and 36 in accordance with the position of the cock 40. This action of the brake cylinder feeder 3 follows very rapidly on all changes of the produced regulating pressure produced by feeding air to or exhausting it from the chamber 32, so that the time needed for adjusting any brake cylinder pressure, in applying as well as in releasing the brakes, precisely depends upon the time needed for adjusting the respective regulating pressures, as above described. Thereby it is possible to apply or release all the brakes of a train precisely at the same time and to any desired degree and without any unduly large braking forces being brought into action.

A temporary overloading of the brake remains innoxious, if for instance in the chamber 8 the pressure amounts to 5 atmospheres and in the chamber 7 to 3.8 atmospheres, and then for rapid release of the brake suddenly 7 atmospheres are produced in the chamber 7, the diaphragm 12 goes upwards, as the valve 24 closes the passage 24a before filling chambers 8, 23 to seven atmospheres, and the regulating pressure in the chambers 5 and 2 and in the brake cylinder chamber 32 begins to fall to the pressure of the atmosphere so as to release the brakes. The diaphragm 12 then returns to its middle position after the leader has again restored the usual pressure of 5 atmospheres in the train pipe. Even if valve 24, 25b should jam during overloading and thereby seven atmospheres be produced in chambers 8 and 23, this remains still innoxious.

For, if thereafter, in order to apply the brakes, a pressure diminution is again produced in the train pipe and chamber 7, then notwithstanding

the pressure of seven atmospheres now existing in chamber 8 and loading the diaphragm 12, the pressure arising in the regulating chambers 2 and 5 does not exceed the maximum desired pressure of 1.2 atmospheres, due to the yielding of the spring 17 which is previously placed under a tension according to the desired maximum regulating pressure of 1.2 atmospheres in chambers 2 and 5. Consequently also the brake cylinder pressure in the chamber 32 does not exceed the desired maximum pressure of, e. g. 3.6 or 2 atmospheres respectively.

If any regulating pressure in the regulating chamber 5, 2 and a corresponding braking pressure in chamber 32 and in the brake cylinder shall be maintained, for instance for a car being out of service, the valve 60 may be closed fully. When a car is to be shunted, the cock 60 is to be closed, before the pressure in chamber 7 is diminished below the maximum train pipe pressure. Thereby a pressure of 0 atmosphere is maintained in the regulation chamber 5, 2 and the brakes are held in release position, when the train pipe is disconnected from the car which is to be shunted. Otherwise, if it is desired to adjust the throttling actions of the throttled passages of the channels 19 and 21, so as to diminish or increase the velocity of the pressure changes in the regulating chamber 2 and correspondingly in the brake cylinder chamber 32, the valve 60 is closed partly, so as to obtain the desired effect.

I claim:

1. A triple valve for direct acting automatic air brakes, comprising a valve for feeding or exhausting air to the brake cylinder, a diaphragm member for governing said valve, a regulating chamber adjoining said diaphragm member, an accelerating chamber of such a volume, that compressed air contained in the latter suffices for filling said regulating chamber up to an initial pressure corresponding to the pressure needed for applying the brake blocks to the car wheels, means governed by the train pipe pressure for connecting or disconnecting said accelerating chamber to or from said regulating chamber, a throttled passage for feeding said accelerating chamber from the train pipe, means depending upon the train pipe pressure for opening or closing said throttled passage, a further throttled passage for exhausting said regulating chamber, and means depending upon the train pipe pressure for opening or closing said throttled exhausting passage.

2. A triple valve for direct acting automatic air brakes as claimed in claim 1, wherein a hand operated valve is inserted in both throttled passages so as to be able to adjust their throttling actions and to fully close them in case of necessity.

FLORENTIN KASANTZEFF.
